United States Patent

Des. 236,620
Patented Sept. 2, 1975

236,620

FIREPLACE HEATER OR SIMILAR ARTICLE

Albert B. Conti, 4 Pine Ridge Road,
Stoneham, Mass. 02180

Filed June 5, 1974, Ser. No. 476,520

Term of patent 14 years

Int. Cl. D23—03

U.S. Cl. D23—97

FIG.1

FIG. 3

FIG. 1 is a top plan view of a fireplace heater or similar article showing my new design;

FIG. 2 is a front elevational view as seen from the bottom of FIG. 1; and

FIG. 3 is a side elevational view as seen from the right and side of FIG. 2, the opposite side of which is identical.

I claim:

The ornamental design for a fireplace heater or similar article, substantially as shown and described.
